O. E. CARTMILL,
TRUNK ATTACHMENT,
APPLICATION FILED NOV. 22, 1920.

1,402,211.

Patented Jan. 3, 1922.

UNITED STATES PATENT OFFICE.

ORRELL EARL CARTMILL, OF STEVENS POINT, WISCONSIN.

TRUNK ATTACHMENT.

1,402,211.

Specification of Letters Patent. Patented Jan. 3, 1922.

Application filed November 22, 1920. Serial No. 425,822.

To all whom it may concern:

Be it known that I, ORRELL EARL CARTMILL, a citizen of the United States, residing at Stevens Point, in the county of Port-

age and State of Wisconsin, have invented certain new and useful Improvements in Trunk Attachments; and I do declare the following to be a full, clear, and exact description of the invention, such as will enable others skilled in the art to which it appertains to make and use the same.

This invention relates to an attachment which is especially, although not necessarily, designed to be used in connection with wheel supported trunks known as "cracker trunks," which type of trunks are used by cracker manufacturers and other manufacturers for shipping their wares and goods.

It is generally well known that great quantities of crackers and cakes and other similar articles are packed in tin boxes to prevent them from becoming broken when being shipped. These boxes are loaded in trunks which hold from eighteen to sixty boxes, and as these trunks are mounted on wheels to permit them to be easily and readily placed on and taken off of the shipping cars, and as there is no device for preventing rolling and movement of the trunks, the contents of the tin boxes oftentimes become broken due to the fact that the various trunks bump into one another during the movement of the train. When the crackers and cakes become damaged from this cause, the railroad company has to undergo unnecessary expense in paying for such damages.

In view of the foregoing circumstances, I have devised an attachment for trunks which permits the latter to be anchored to the floor of the car, thus preventing relative movement of the various trunks and, of course, preventing breakage of the contents of the aforesaid boxes.

The principal object of the invention is to provide an attachment for accomplishing the above results which is extremely simple in construction, strong, durable, and very inexpensive to both the manufacturer and the user.

Another and very important object of the invention is to provide an attachment of the above mentioned class which includes an anchoring arm and a retaining clip for holding the arm in an out of the way position

when the device is not in use, thus preventing the same from becoming accidentally displaced by contact with the sides of the car or with other trunks.

Other objects and advantages of the invention will be apparent during the course of the following description.

In the accompanying drawings forming a part of this specification and in which like numerals are employed to designate like parts throughout the same:

Figure 1 is an elevational view of the lower portion of a cracker trunk showing my improved attachment in position thereon.

Figure 2 is an enlarged view taken on the plane of the line 2—2 of Fig. 1, the device being shown in the position that it assumes when it is not in use.

Figure 3 is a view similar to Fig. 2 showing the manner in which the device is used.

Figure 4 is a detail perspective view of an attachment constructed in accordance with this invention.

Figure 5 is a detail perspective view of the retaining clip.

Figure 6 is a slightly enlarged top plan view of a portion of the attachment, showing more clearly the hinge for attachment to the floor of the car.

Referring to the drawings, wherein the preferred embodiment of the invention is clearly illustrated, it will be seen that the letter T designates a wheel-supported trunk of the type used for transporting boxes containing crackers and the like. Attached to the bottom of this trunk in the position shown, by means of a suitable attaching bracket 2, is a movable arm or rod 3 provided at its outer end with a suitable device 4 designed to be connected to the floor F of a car. The above referred to parts may be of any suitable construction and arrangement, the part 2 being here shown in the form of an inverted U-shaped bracket

equipped with an attaching screw 5 by means of which it is easily and readily secured to the bottom of the trunk. The arm 3 is flattened at one end and this end is disposed between the arms of said bracket 2 and pivotally connected thereto by means of a bolt 6. At its outer end, this arm 3 is preferably provided with a pair of oppositely extending headed studs 7 which constitute pintles for the pivoted anchoring plate 4. This plate could be of any other construction, but I prefer to employ a leaf

of an ordinary gate hinge for the purpose. With such a hinge, a nail or screw may be passed through one of the openings therein and through the floor of the car body. 5 Thus, the arm can be easily anchored and when it is necessary to unload the car, the plate 4 may be pried up and disconnected from the floor very easily and readily. It is to be noted that the device is to be so 10 placed on the trunk, that the outer end of the anchoring arm 3 will not extend beyond the adjacent vertical wall of the trunk. This is done to prevent this arm from becoming struck by one of the adjacent trunks and 15 also to prevent the arm from striking the wall of the car.

It is desirable to retain the arm and hinge-plate 4 in an out-of-the-way position when the device is not in use. To this end, 20 I make use of a suitable resilient clip 8 which, as is obvious, will retain the parts in the position disclosed in Fig. 2. The clip may be secured to the bottom of the car body by means of a bolt 9 or any other 25 suitable fastening device and if desired, the free ends thereof could be flared outwardly away from each other to facilitate insertion of the arm 3.

In use, it is understood that the trunks 30 are shoved into the car and placed in the desired positions therein. Assuming that each trunk is equipped with an attachment of the type set forth, it will be seen that the arm 3 may be disengaged from the clip 8 35 and moved to the position shown in Fig. 3, after which the plate 4 may be detachably connected to the floor of the car by means of a nail or screw. Thus, the trunk is anchored and is prevented from moving about 40 the floor of the car. When it is necessary to unload the car, all the freight handlers have to do is to pry up the plate 4 and move the arm 3 upwardly, whereby the latter will become engaged by the aforesaid clip and 45 will be retained in an out-of-the-way position.

From the foregoing description, it will be seen that I have devised an extremely effective and simple attachment for trunks 50 which permits the latter to be anchored to the floor of a car and thus prevented against movement. The parts which are employed to make up the device are extremely strong and durable and there are no parts to be 55 come disarranged or get out of order. The anchoring arm is entirely protected when not in use and will not become broken because of contact with other trunks or other obstacles. The device is easy to attach and 60 detach and will not interfere with easy loading and unloading of the trunks to and from the car as the case may be.

A careful consideration of the foregoing description taken in connection with the 65 accompanying drawings, is thought to be

sufficient to enable persons skilled in the art to which this invention relates, to obtain a clear understanding of the same, therefore, a more lengthy description is deemed unnecessary.

70 Advantageous and effective results are insured with an attachment of the construction shown and described and this construction and arrangement is taken as the preferred embodiment of the invention. 75 However, I wish it to be understood that various minor changes in the shape, size, and arrangement of parts may be resorted to without departing from the spirit of the invention or the scope of the subjoined 80 claims.

I claim:

1. In combination, a wheel supported article carrier, an anchoring arm hingedly connected to said carrier and extending 85 longitudinally of the carrier beneath the same, the anchoring arm being foldable upwardly beneath the carrier when out of use to position it out of the way, and floor engaging means pivotally connected with the 90 free end of said anchoring arm and adapted to hang downwardly from the anchoring arm when the anchoring arm is in a raised position.

2. The structure set forth in claim 1, 95 there being a spring clip on the carrier for holding the arm in an ineffective position.

3. A device of the class described comprising an anchoring arm, means for pivotally connecting one end of said anchoring 100 arm to a wheel supported article carrier, and securing means pivotally connected with the opposite end of said anchoring arm and adapted for connection to the floor of a shipping vehicle.

105 4. A device of the class described comprising a rod, an attaching bracket pivotally connected to one end of the latter and adapted for attachment to the bottom of a wheel supported trunk, and an anchoring plate 110 pivotally connected to the opposite end of said rod.

5. A device of the class described comprising a rod provided at one end with a pair of oppositely disposed laterally extending 115 pintles, a hinge-leaf pivoted on said pintles, and means carried by the opposite end of said rod for connecting the latter to a wheel-supported article carrier.

120 6. A device of the class described comprising a rod apertured at one of its ends, a U-shaped attaching bracket, the arms of which are provided with aligned apertures, said apertured end of the rod being positioned beneath said arms, a pivot passing 125 through the apertures in the arms and rod, said bracket including an attaching screw, and means carried by said rod for anchoring it to a stationary support.

7. The structure as set forth in claim 3, 130

and a retaining clip adapted to be connected with the shipping vehicle in position for engaging said rod and retaining the latter in an out-of-the-way position.

- 5 8. A device of the class described, comprising a rod, apertured at one of its ends and provided at its opposite end with a pair of oppositely disposed pivot pintles, an apertured anchoring plate pivotally connected to said pintles, a U-shaped apertured attaching bracket, including a screw, the

apertured end of said rod being positioned between the arms of said bracket and the aperture thereof being in alinement with the apertures in said arms, a removable pivot 15 pin extending through said apertures, and a resilient U-shaped retaining clip associated with said rod.

In testimony whereof I have hereunto set my hand.

ORRELL EARL CARTMILL.
